MACHINE FOR MAKING WIRE GARMENT-STAYS.

1,123,824.

Specification of Letters Patent.

Patented Jan. 5, 1915.

Application filed October 28, 1912, Serial No. 728,277. Renewed October 21, 1914. Serial No. 867,898.

To all whom it may concern:

Be it known that I, FRANK L. O. WADSWORTH, a resident of Sewickley, in the county of Allegheny and State of Pennsylvania, have invented a new and useful Improvement in Machines for Making Wire Garment-Stays, of which the following is a specification.

This invention relates to wire bending machines, and more particularly to a machine for bending wire back and forth into successive oppositely disposed loops to form corset stays, such for instance as shown in Patent No. 507,875, granted October 31, 15 1893 to Marcus M. Beeman.

The invention in some particulars comprises certain improvements upon prior machines for making such stays, such for instance as illustrated and described in Patent No. 1,009,823, granted November 28, 20 1911 to Marcus M. Beeman, and that illustrated, described and claimed in Letters Patent granted to Marcus M. Beeman and John F. Kitchen, October 29, 1912, No. 25 1,042,756.

The objects of the invention are; first, to make the machine adjustable while it is running in order to eliminate edgewise curvature in the fabricated stay; second, 30 to obtain a more effective stroke and thrust of the bending fingers by means of an improved arrangement of mechanism for oscillating the bending fingers; and third, to simplify and improve certain other features 35 of construction and operation as will hereinafter appear.

Another object of the invention is to provide machines of this same general character with means for imparting a twist or torsional set to the wire in order to form a stay possessing greater resiliency and greater ability to resist a permanent set or distortion, and which also is stiffer in one flatwise direction than in the other, thereby 45 enabling the stay to be made of lighter wire without being rendered unduly flexible.

The invention comprises the construction and arrangement of parts hereinafter described and claimed.

In the accompanying drawings, Figure 1 50 is a side elevation of the improved machine; Fig. 2 is in part a plan view and in part a horizontal section on the line 2--2, Fig. 1; Fig. 3 is a transverse vertical section on the

line 3--3, Figs. 1 and 4; Fig. 4 is a longitudinal vertical section on the line 4--4, 55 Fig. 3; Fig. 5 is a longitudinal section on the line 5--5, Fig. 4; Fig. 6 is a cross section on the line 6--6, Fig. 5; Figs. 7 and 8 are diagrammatic views; and Figs. 9 and 10 are respectively side elevation and plan 60 views of a modified form of machine, certain parts being omitted.

The specific machine illustrated is provided with a suitable base 1 upon which are 65 erected the necessary frames or standards carrying the operative parts of the machine. The machine will be provided with a suitable flattening device for straightening the fabricated stay and with reeling 70 mechanism therefor, the same as in the patents above identified, but as neither of these is involved in the improvements employed by the present invention they are not illustrated. The machine may also be 75 equipped with a suitable device M for cleaning the wire and with a tension device N of any preferred type. As shown, there is erected upon the base a suitable frame 2 on which all of the operative parts of the machine are mounted. This frame, preferably, 80 is a casting comprising a pair of side plates or walls 3 parallel to each other, a rear wall 4 uniting said side walls, a front plate 4^a, and a bottom 5 by means of which said 85 frame is secured to the base 1. The side walls are provided with suitable bearings 6 for the main shaft 7, which extends at both ends beyond said side walls, at one end being provided with the fast and loose pulleys 8 and 9 by means of which the machine 90 is driven, and on its opposite end being provided with the hand wheel 10 for turning said shaft by hand, and inside of said hand wheel with a gear 11 which meshes 95 with a gear of similar size 12 on a counter shaft 13 mounted in suitable bearings 14 in the side walls of the frame 2. The counter shaft 13 has secured thereto a miter gear 15, which meshes with a similar gear 16 on 100 a vertical shaft 17 mounted in suitable bearings 18 on the rear wall 4 of the frame. Shaft 17 at its upper end is provided with gear 20 meshing with a similar gear 21 on another vertical shaft 22 also mounted in 105 suitable bearings 23 on the rear wall 4 of the frame. The shafts 17 and 22 are symmetrically arranged with reference to the

central longitudinal plane of the machine, one on each side thereof, and both shafts are rotated at the same speed but in opposite directions. Each of said shafts is provided at its upper end with a crank 24 carrying a wrist pin 25 connected by link 26 with a wrist pin 27 on one arm of a bent lever 28, fulcrumed on the pin or shaft 29 and having its other arm provided with 10 wrist pin 30 on which works the connecting rod 31 for operating the oscillating bending finger hereinafter described. The fulcrum 29 of each of the levers 28 is mounted in a suitable bearing member 32 longitudinally 15 adjustable on the frame 2, such as by being provided with slots 33 through which pass the clamping bolts 34. Preferably, positive means are provided for longitudinally adjusting said bearing members 32, such as 20 screws 35 rotatable in lugs 36 on the frame and having a threaded engagement, as at 37, with the bearing member 32 and provided with a suitable wheel or head 38 for turning the same. It will be readily apparent that 25 by loosening the bolts 34, the bearing members 32 can be adjusted longitudinally by means of the screws 35 to vary the position of the fulcrum 29 of the bent levers 28, and that this adjustment may be made while the 30 machine is in motion. This adjustment has for its purpose to vary the throw of the bending fingers, as will hereinafter more fully appear.

The bending devices comprise a pair of 35 vertically movable members carrying anvil pins around which the wire is bent, and a pair of oppositely located oscillating bending fingers of the same general design as in the patents above referred to, but differing 40 in detail. The anvil pins 40 and 40^a are arranged in pairs, each pair being secured to a suitable pin block 41 secured to the upper end of a vertically reciprocating and oscillatory carrier, said carriers being marked 45 42 and 42^a respectively. The front plate 4^a is secured directly to the side walls 3 of the frame by bolts 121, and carries on its inner face the fixed members of split bearings 122, the other removable members thereof being 50 secured to the plate by bolts 123. In the bearings 122, which are located just above the main shaft 7, are journaled the trunnions 43 of oppositely arranged rocker guides 44 which are grooved on their facing 55 sides and in which the pin block carriers 42 and 42^a are respectively mounted so as to slide vertically therein, as clearly illustrated in Figs. 3 and 4. Wearing strips 46 are interposed between the edges of the pin block 60 carriers and the grooves in guides 44. Each pin block carrier at its lower end is provided with roller 47, which rollers engage respectively in cam grooves 48, 48^a cut in members 49 and 49^a secured to the main 65 shaft 7. These cams are not only oppositely

arranged with reference to the central vertical plane of the machine but are also set on the shaft 7 at an angle of 180° from each other, (cam 48 being shown in dotted lines in Fig. 4), so that they impart vertical reciprocating movements alternately to the pin block carriers 42 and 42^a. The cam grooves serve to both positively elevate and also positively retract the pin block carriers, and also oscillate them on the trunnions 43 to feed the fabric through the machine. These cams are so shaped as to give relative rigid reciprocatory movements to the pin block carriers allowing for a very considerable pause in movement both in the elevated and the depressed positions of said pin block carriers, for a purpose which will hereinafter appear.

The coöperating bending members comprise a pair of oscillatory bending fingers 51 and 51^a, each secured to a suitable holder 52 mounted to oscillate on a vertical stud or trunnion 53 and provided with an arm 54 to which the connecting rod 31 is pivotally connected at 55. Each trunnion 53 is 90 mounted in a bearing member 56, secured to the main frame by means of bolts 58 and having a rounded boss or projection 57 engaging the frame and on which the bearing member rocks. A set screw 59 is threaded 95 through the swinging bending frame 56 and impinges against the main frame and serves as a means for adjusting the center of oscillation 53 of the bending member around pivot 57 toward and from the central longitudinal plane of the machine, as will be 100 readily apparent. The means for longitudinally adjusting the bearing members 32, heretofore described, serves to vary the extent to which the bending fingers oscillate 105 or move inwardly; and this means when used in conjunction with the lateral adjustment for the bearing members 56, 56 affords an accurate and convenient means for securing uniformity of throw between the two 110 bending fingers thereby preventing the stay which is being fabricated from acquiring any edgewise curvature or bend.

Each bending finger 51, 51^a is made in the form of a plate adjustably clamped to 115 the holders 52, 52, by means of the small bolts 60, passing through slots 60^a in the plates, and these plates can be adjusted in height with reference to the other parts by placing liners under them. These fingers 120 are provided in their ends with grooves 65 for catching the unformed portion of the wire and bending the same around the pins 40 and 40^a. The unformed portion of the wire is indicated at 67 and a portion of the 125 fabricated stay at 68, the latter being formed between the pin blocks and a superimposed adjustable presser foot or plate 69, similar to that used in the Beeman and Beeman and Kitchen machines, above identified. 130

The operation of this part of the machine in its general characteristics is similar to that of the Beeman and Kitchen machine referred to above. The differences consist, 5 principally in a different mechanism for actuating the bending fingers, whereby the throw of the latter can be adjusted without stopping the machine, as previously explained; in a different mode of producing 10 the oscillating movement of the said fingers whereby the necessary range of movement or arc of oscillation is greatly reduced and a long pause secured at the end of the outward swing; and in a different 15 shape of cam for actuating the pin block carriers whereby the latter are held longer in their elevated positions for the purpose of giving time for certain wire twisting operations hereinafter to be described. The 20 change in the mechanism for reciprocating the pin block carriers is largely merely a change in the design of the cams, but the mechanism for oscillating the bending fingers is of an entirely different type, and 25 produces a decidedly different character of oscillatory movement particularly designed and adapted to secure the necessary periods of comparative rest for the actuation of the wire twisting mechanism, before the bending 30 finger moves inwardly to catch the wire.

The wire twisting mechanism comprises a suitable gripping member or clutch formed of two or more jaws 70 between which the wire 67 passes and arranged at 35 the proper time to be brought together to grip the wire and then rotate it. The specific means for effecting this, comprises a suitable jaw holder 72 in which the jaws 70 are mounted and provided with co-operating 40 tapered faces 71 so that when the jaws are moved endwise into the holder, they are caused to approach each other and clamp the wire, and when retracted they separate and release the wire. The jaws are pushed 45 into the holder by means of a pair of levers 73, oppositely arranged and each mounted upon a fulcrum 74 on holder 72 and having a cam face 75 engaging the rear end of a jaw 70. Connected to the free end of each 50 lever is a link 76, said links being pivotally connected at 76^a to a sliding member 77, which is provided with an orifice through which the wire passes and the outer end of which is provided with a grooved collar 78 55 which is engaged by the forked end 79 of a bell-crank lever 80, pivoted at 81 and having its opposite arm connected by a collar 82 to a vertically reciprocating sleeve 83 carried on a shaft 84. The sleeve 83 is connected by a rod or bar 83^a to one end of a lever 85 fulcrumed to the frame at 86 and carrying intermediate its ends a roller 87 which is engaged by a cam 88 on the main shaft between the two cams 49 and 49^a. 60 The depression of the lever 85 actuates

bell-crank lever 80 to push inwardly on the member 77 and straighten out the toggle links 76, thereby spreading the levers 73 and causing the cam portions 75 to push the jaws 70 into the jaw holder 72 and grip the wire. The movement of the lever 85 in the opposite direction permits the member 77 to move outwardly to flex the toggle members 76 and draw the cam levers 73 toward each other. These levers are positively connected to the jaws by means of the hooked members 90, so that the jaws are positively retracted to release the grip on the wire. A spring 91 is preferably employed to move the lever 85 in the direction opposite to that in which it is moved by the cam 88. The cam 88 is so arranged that the jaws 70 grip the wire twice for each complete rotation of the main shaft 7, so that the wire is gripped once for each oscillation of each of the bending fingers. 80

The jaw holder 72 is mounted in a suitable frame 93 having a movement of oscillation about the axis of the shaft 84, so that the gripping member may swing back and forth 90 to accommodate itself to the varying angle which the wire assumes when being bent back and forth by the oppositely moving bending fingers. The amount of lateral movement of frame 93 to one side or the other is limited by adjustable stops 120 secured to fixed portions of the main frame and which are contacted by frame 93. In order to twist the wire when gripped, first in one direction and then in the other, the following mechanism is provided: The jaw holder 72 is rotatably mounted in the frame 93 and is provided with a miter gear 96 which meshes with a similar gear 97 mounted on the lower end of a short stud 98 in the frame 93. The miter gear 97 is secured to a pinion 99 which is engaged by a segmental gear 100 on the inner face of an annular member 101, which is rotatable on the stud 94, axially in line with the shaft 84. The annular member 101 and the segmental gear 100 secured thereto are given a rotary oscillatory movement, first in one direction and then in the other by the following means: 102 represents each of a pair of arms pivoted on the stud 94 and provided with a slot 103 for receiving the adjustable block 104 to which is pivoted one end of the connecting rod 105, the opposite end of said rod being slidable through a collar 106 on the lever 54 of the bending member supports. Nuts 107 and 108 on threaded portions of the rod 105 provide a convenient means for varying the amount of lost motion between the oscillating bending arm 125 54 and the connecting rod 105, while the slots 103 provide a means for varying the amplitude of oscillatory movement that may be imparted to the arms 102. Each arm at its outer end carries a pawl 110 co- 130

operating with ratchet teeth 111 on the outer face of annular member 101. Each of the pawls 110 is provided with a projection 112 adapted to contact with a stop pin 113, 5 adjustable around shaft 94 as a center, in a slotted arm on the frame of the machine. The operation of this part of the machine is as follows: After each bending finger has advanced and formed a crossing and eye 10 portion, it is retracted to the position shown at the right of Fig. 2 and the pin block under the last formed eye then rises and clamps the wire between it and the presser foot 68. Coincidently with this upward 15 movement of the pin block the cam 88 engages with the roller 87 and pushes the jaws 70 into the jaw holder 72 so that they grip the wire. As the bending finger carrier 52 continues to oscillate backwardly, its arm 54 20 engages the nuts 107 on the end of the connecting rod 105, thereby imparting an oscillatory movement to the arm 102 and causing the pawl 110 to engage with the ratchet teeth 111 to rotate the annular member 101, 25 and this in turn imparts a rotary movement to the gripper jaws 70, thereby imparting a twist in one direction to that portion of the wire between the pin around which it is looped and the end of the gripping jaws 70. 30 The amount of such twist can be varied by adjusting the bolt 104 in the slot 103. During this backward movement of one of the bending finger carriers and the resultant forward movement of one of the arms 102, the 35 other bending finger carrier and arm are standing practically at rest with the opposite pawl 110 in such position that its projection 112 is in contact with pin 113, and the pawl is out of engagement with the ratchet 40 teeth. Near the end of the backward movement of the bending finger the pawl on the forwardly moving arm 102 engages with its pin 113 and is thereby lifted out of engagement with the teeth 111 and the cam 88 45 then releases the end of the lever 85 and allows the latter to be moved by the spring 91, thereby retracting the gripping jaws 70 and releasing the wire. The pin block next to the backwardly moving bending finger 50 then drops, and the opposite bending finger 51^a and its carrier simultaneously swing inwardly to bend the just twisted portion of the wire into the next loop. As this bending finger swings inwardly it at first does 55 not move the opposite pawl arm 102, but as soon as its arm 54 contacts with the nuts 108, the opposite pawl arm is swung backwardly, the pawl moving idly over the ratchet teeth, this bringing it to such position that when said bending finger 51^a is retracted the annular member 101 is rotated 60 in the opposite direction, thereby rotating the twisting jaws 70 in the reverse direction to that in which they were before rotated 65 and twisting the portion of the wire be-

tween the twisting jaws and the last pin in a direction opposite to that in which the previous portion was twisted. The several parts are so timed, that the gripping jaws are forced into the holder 72 before the latter 70 begins to rotate, and after the appropriate pin block carrier has been elevated to grip the formed crossing of the wire.

Fig. 7 illustrates diagrammatically on a scale corresponding to that of Fig. 1, the relations to each other, during one complete cycle of steps, of the mechanism for operating one of the bending fingers and the twisting device. In that view A represents graphically the axis of the vertical shaft 22; 75 B represents the axis of reciprocation of the bent lever 28; C is the axis of the trunnion 53, around which the bending finger swings or oscillates; and D is the axis of shaft 94, 80 around which the annular member 101 oscillates to impart a twist to the wire. The positions of the various parts, during the cycle of movement, are numbered in order from 0 to 16, 0 and 16 being the starting and end positions. In this cycle the crank pin 25 85 makes one complete revolution on the axis A in the direction of the arrow *a*. During the same cycle of movement, the wrist pin 27 on the short arm of the lever 28 oscillates through the arc *a*—*b*, *b*—*a*, and the wrist pin 30 on the long arm of the lever 28 oscillates through a corresponding arc *c*—*d*, and then back again through the same arc *d*—*c*. The corresponding oscillatory movement of the arm, carrying the bending finger on the 90 axis C is laid out on the projected sector *e*—*f*, and as there shown the initial movement of the parts from the position 0 to position 3 moves the said arm and finger slightly outwardly away from the central plane of the machine and the loop forming pins. The continued movement of the parts from the 95 position 3 to position 8 then carries the bending finger inwardly to engage the wire and bend the same around the loop forming pin. This motion begins slowly and increases rapidly and is followed by a quick retreat of the bending finger away from the loop forming pin to about the position 12, where the outward movement becomes gradually slower 100 and slower until the initial positions of the parts is reached at 16. Fig. 7 also illustrates the movement of the arm 102 and pawl 110 which swings or oscillates the annular member 101 to impart a twist or torsional set to the unformed portion of the wire. Referring again to that figure, as the arm 54 swings from position 0 to about position 6, the collar 106 slides on the rod 105 with a lost motion effect, and there is no motion of arm 102. This takes place during the first portion of inward swing of the bending finger. The collar 106 then contacts with nuts 108, 105 at about position 6, and a further swing of arm 54 carries the pawl 110 rearwardly over 110

the ratchet teeth until the parts reach position 8, when the bending finger is at its inner limit of movement.

In the backward or reverse movement of 5 the parts from the position 8 to a position between 9 and 10, the collar slides on the rod 105 without moving the arm 102 and during this time the bending finger is withdrawn from the wire and the cam 49 or 49^a raises 10 the proper pin block carrier and the loop forming pins clamping the last formed loop in place under the presser foot 69. At the same time cam 88 engages roller 77 and the jaws 70 are operated to grip the wire. Further 15 backward movement of the arm 54 to about position 13 then swings arm 102 forward, during which movement the jaws 70 are rotated in the direction to impart the proper twist to the wire. The jaws are rotated twice during each cycle of movement, 20 first in one direction by the backward swing of one bending finger arm and then in the other by the backward swing of the other bending arm. It will be observed also that 25 this rotation always takes place while one finger is retreating from the wire, and is fully completed just as the other bending finger begins to move inwardly to bend the wire around the next pin, the length of the 30 clamping cam arcs 88 being such that the clamp jaws are released just before the advancing finger engages with the twisted section of wire between said jaws and the previously formed and clamped loop.

35 The advantage of this new type of oscillatory or reciprocatory drive mechanism is best shown by the velocity ratio diagram of Fig. 8. In this diagram the line curve marked "y" indicates, by the ordinate of 40 the curve, the movement of the bending finger from its extreme position of retraction to the various positions which it occupies in the forward bending movement by which the eyes or loops of one edge of the wire stay 45 body—say the left hand edge—are formed. The ordinate of the line curve y^1 correspondingly indicates the position occupied by the end of the opposite bending finger at the same intervals of time. Examination of 50 the diagram readily shows that practically the entire oscillatory movement of each bending finger is accomplished in about one-half of a complete revolution of the main driving shaft of the machine, and that the 55 bending finger remains at rest at or near its extreme position of retraction for nearly one-half of a complete revolution. In consequence of this the bending finger which has last formed its loops or eyes can be 60 completely swung back to its extreme position of retraction—and the twisting of the wire which is accomplished during this backward swing completely finished—before the opposing bending finger begins its forward 65 movement. The long interval of rest

at the position of extreme retraction also allows plenty of time for the movements of the pin blocks and for the clamping and unclamping of the wire gripping chuck; and also, as previously stated, permits the 70 use of a shorter total swing in the bending finger movements than is necessary when the said fingers are driven directly from a rotative crank element as in the form of stay bending machine earlier referred to in this 75 specification.

The twisting of successive portions of the wire in opposite directions is necessary in order that the twist in all of the crossings or transverse portions of the wire, viewing 80 the stay as a whole, shall run in the same direction, as otherwise the twist in adjacent crossings would neutralize each other. The distance between the gripping jaws 70 and the pin around which the wire is looped 85 must be substantially equal to the length of one of the crossing portions of the wire in order that the twist may be confined to the proper length of wire. It is on account of the necessity of the close proximity of the 90 twisting jaws to the pin blocks that the bending fingers can have only limited oscillatory movement and because of the time intervals necessary to rotate the twisting jaws, it is necessary that the bending fingers have 95 a very material pause at the outer limit of their movement. The twisting mechanism could, of course, be omitted, in which case the machine would operate to produce a stay having the same general characteristics 100 as the stay produced by the Beeman and Kitchen machine above identified, with the advantage that the stroke of the bending fingers can be adjusted without stopping the machine, thereby making it possible to prevent edgewise curvature in the stay, which is characteristic of prior machines due to the fact that both bending fingers do not always oscillate to the same extent beyond the central longitudinal plane of the machine. 110

Figs. 9 and 10 illustrate another arrangement of mechanism for rotating the twisting jaws and jaw holder, to impart a torsional set or initial twist alternately in opposite directions to successive portions of the wire. This mechanism is more nearly like that described and shown in my prior companion application for method of making garment stays, filed July 1, 1912, Serial 115 No. 706,956. In this construction the arrangement of cams, gears, cranks, and lever connections for operating the bending fingers, the pin blocks and clamp jaws is the same as in the machine shown in Figs. 1 to 120 6, and therefore requires no further description. The mechanism for rotating the twisting jaws is as follows: Upon shaft 13, and between the gear 12 and the side plate 3 of the main frame, is mounted a cam 125, into 125

the groove or track 126 of which projects a pin or roller 127 on a lever 128 pivotally connected at one end, as at 129, to a fixed portion of the frame. At its other end lever 5 128 is connected by a link 130 to a pin or bolt 131 adjustable in the slot 132 of an arm 133 which is rigidly secured to a shaft 134 journaled in a bracket on the front plate 4^a. Shaft 134, at its other end, is provided with 10 a bevel gear segment 135 meshing with a bevel gear 136 loosely rotatable on a shaft 137 which supports the swinging frame 93 carrying the twisting jaws and chuck. Gear 136 is either fixed to or integral with a spur 15 gear 138 which meshes with and drives a similar gear 139 on the lower end of a short stub shaft journaled in frame 93 and carrying a bevel gear 140 at its other end, said bevel gear 140 meshing with and driving 20 the miter gear 96 of jaw holder 72. The cam track or groove 126 in the cam 125 is formed with oppositely inclined portions 141, which are arranged opposite to each other and at their ends are connected by the 25 inner and outer circular portions of the track, marked respectively 142 and 143. Whenever the inclined portions 141 of the cam track engage the roller 127 the lever 128 is swung in one direction or the other. 30 Lever 128, through the link 130, swings or oscillates shaft 134 and bevel gear segment 135, which in turn, through the gears 136, 138, 139, 140 and 96, rotates the gripping jaws 70 and jaw holder 72 alternately in 35 opposite directions. The amplitude of angular rotation of the jaw holder and jaws may be varied by adjusting the pin or bolt 131 in the slot 132, which is radially disposed with reference to the axis of shaft 40 134. This causes varying movements of oscillation to be given to shaft 134 with the same amount of swing or oscillation of lever 128 on its pivot 129.

The operation of this machine is the same 45 as that shown in Figs. 1 to 6, the chuck rotating mechanism being shown in a position which corresponds to the position of parts illustrated in these figures. As the bending finger on the right hand side of the 50 machine is retracted the pin block on the left hand side of the machine is raised to engage with the last formed loop or eye; the wire is simultaneously gripped or clamped by the jaws 72; and the latter are then rotated through the desired angle by the action of the cam 125. The latter is secured 55 on the shaft 13 in such position that one inclined portion 141 engages with the roller pin 127 and moves it and the lever 128 to 60 the left while the retreating bending finger is completing its backward movement, thereby imparting the desired twist to the wire just before the opposite bending finger comes in from the left hand side and en-

gages the wire to bend it laterally to form 65 the next crossing and eye. The clamp jaws are then released and held stationary (by the engagement of the roller pin 127 with the outer circular portion 143 of the cam track) until the next loop or eye is formed, 70 after which the corresponding pin block is raised. The clamp jaws are now closed and rotated in the opposite direction by the engagement of the roller pin 127 with the other inclined portion 141 of the cam 125. 75 This form of machine may also be provided with a suitable tension device for holding the wire taut as it enters the machine, the drawings illustrating at 150 the same form of tension device shown in the Patent No. 80 1,009,823 to Beeman heretofore referred to.

Various modifications obviously can be made in the construction and arrangement of parts without departing from the spirit of the invention. It is obvious, for example, that the machine above illustrated and described could be used in forming twisted plural wire stays—such as form the subject matter of my application, Serial No. 710,007, filed July 17, 1912,—by simply replacing the split chuck by a solid die head having separate perforations for each of the wires of the plural wire stay. In this case no clamping or unclamping mechanism is necessary, because the wires are twisted and braided together by the rotation of the die head itself, a sufficient length of the twisted or braided section being formed at each rotative movement of the said die part to form the next crossing and loop of the said 100 body. A similar arrangement to that last described could also be used in forming rectangular twisted wire stays such as are illustrated and described in my co-pending application Serial No. 710,006, filed July 17, 105 1912. In this case the rotating die is provided with an opening corresponding to the cross-section of the wire to be used, and successive portions of this wire are twisted first in one direction and then in the other 110 by corresponding rotative movements of the die.

What I claim is:

1. In a wire bending machine, the combination of alternately movable anvil members, oscillating benders arranged to bend the wire against said anvil members, mechanism for oscillating such benders alternately, and means operable while the machine is in motion for varying the throw of 120 said benders.

2. In a wire bending machine, the combination of alternately movable anvil members, oscillating benders arranged to bend the wire against said anvil members, and mechanism for oscillating said benders alternately, said mechanism including adjustable means adapted to be operated while 125

the machine is in motion and arranged to vary the throw of either of said benders.

3. In a wire bending machine, the combination of alternately movable anvil members, oscillating benders arranged to bend the wire against said anvil members, and mechanism for oscillating said benders alternately, said mechanism including means for adjusting the throw of one of said benders independently of the other while the machine is in motion.

4. In a wire bending machine embodying alternately movable anvil members and oscillating benders arranged to bend the wire against said anvil members, means for oscillating one of said benders, said oscillating means including a lever, and means for shifting the fulcrum of said lever, whereby the throw of said bender is varied.

20 5. In a wire bending machine embodying alternately movable anvil members and oscillatory benders coöperating therewith, means for oscillating one of said benders comprising a rotating crank, a pivoted lever, operating connections from one end of said lever to said crank, and operating connections from the other end of said lever to said bender.

30 6. In a wire bending machine embodying alternately movable anvil members and oscillatory benders coöperating therewith, means for oscillating one of said benders comprising a rotary shaft carrying a crank, a bent lever fulcrumed at its angle, an operating rod connecting one end of said lever to said crank, and an operating rod connecting the opposite end of said lever with said oscillatory bender.

40 7. In a wire bending machine embodying alternately movable anvil members and oscillatory benders coöperating therewith, mechanism for oscillating one of said benders, means operable when the machine is in motion for varying the motion of said bender, and means for adjusting the axis around which said bender swings toward and from the central line of the machine.

50 8. In a wire bending machine embodying alternately movable anvil members and oscillatory benders coöperating therewith, mechanism for actuating one of said benders including an oscillating lever, means for shifting the fulcrum of said lever to vary the position of said bender, and means for 55 also shifting the axis around which said bender swings.

9. In a wire bending machine embodying alternately movable anvil members and oscillatory benders coöperating therewith, bearing members on which said benders are mounted, means for adjusting said bearing members toward and from the central line of the machine, and means for oscillating one of said benders including an oscillatory

lever, a bearing member on which the same is fulcrumed, and means for adjusting said bearing member longitudinally of the machine.

10. In a wire bending machine embodying bending devices, the combination of a wire twisting device located in proximity to said bending devices, and means for causing the twisting device to periodically engage the unformed portion of the wire and twist the same.

75 11. In a wire bending machine embodying bending devices, the combination of a wire twisting device located in proximity to said bending devices, and means for causing said twisting device to periodically engage the unformed portion of the wire and twist successive portions thereof alternately in opposite directions.

12. In a wire bending machine embodying bending devices, a wire twisting device located in proximity to said bending devices and through which the wire is fed, and means for causing said twisting device to periodically engage the unformed portion of the wire as it is fed to said bending devices and twist the same.

85 13. In a wire bending machine embodying bending devices, a wire twisting device located in proximity to said bending devices and through which the wire passes thereto, and means for causing said twisting device to periodically engage the unformed portion of the wire as it passes to said bending devices and twist successive portions thereof alternately in opposite directions.

95 100 14. In a wire bending machine embodying bending devices, the combination of a wire twisting device located in proximity to said bending devices, means for causing said twisting device to grip the wire, and means for rotating said twisting device as it grips the wire to impart a twist or torsional set thereto.

110 15. In a wire bending machine embodying bending devices, the combination of a wire twisting device located in proximity to said bending devices, means for causing said twisting device to periodically grip the unformed portion of the wire, and means for rotating said twisting device alternately in opposite directions during successive gripplings of the wire, said twisting device being arranged to release the wire between successive rotations thereof.

115 120 16. In a wire bending machine embodying bending devices, the combination of a wire twisting device located in proximity to said bending devices, said wire twisting device comprising a clutch, means for periodically closing said clutch to grip the wire, and means for rotating said clutch when closed.

125 17. In a wire bending machine embodying bending devices, the combination of a wire

twisting device located in proximity to said bending devices, said twisting device comprising a clutch through which the wire is fed to the bending devices, means for periodically closing said clutch to grip the wire, and means for alternately rotating said clutch in opposite directions during successive grippings of the wire, to thereby impart a twist or torsional set thereto.

10 18. In a wire bending machine embodying bending devices, the combination of a wire twisting device located in proximity to said bending devices, said wire twisting device comprising a clutch, means for periodically closing said clutch to grip the wire, and means for rotating said clutch when closed, said means including a gear, and means for rotating said gear intermittently and in opposite directions.

20 19. In a wire bending machine embodying bending devices, the combination of a wire twisting device located in proximity to said bending devices, means arranged to cause said twisting device to successively grip and release said wire, and mechanism for rotating said twisting device during successive grippings of the wire first in one direction and then in the other to impart a twist or torsional set in opposite directions

30 thereto.

20 20. In a wire bending machine, the combination of bending devices, a wire twisting device located in proximity to said bending devices, means for causing said twisting device to periodically grip the wire, and means for rotating said twisting device comprising an oscillatory member connected thereto and carrying a ratchet, and a lever carrying a pawl for swinging said oscillatory member.

40 21. In a wire bending machine, the combination of bending devices, means for operating the same, a wire twisting device located in proximity to said bending devices, means for causing said twisting device to periodically grip the wire, and means controlled by said bending device operating means for rotating said twisting device in synchronism therewith.

50 22. In a wire bending machine, the combination of bending devices, a wire twisting device located in proximity to said bending devices, and means for causing said twisting device to alternately twist successive portions of the wire in opposite directions, said means being connected to said bending devices and operating in synchronism therewith.

60 23. In a wire bending machine, the combination of alternately movable bending devices, a wire twisting device located in proximity to said bending devices, and connections from said bending devices to said wire twisting device and arranged to alter-

nately operate the same to impart a twist or torsional set in opposite directions to successive portions of the wire.

24. In a wire bending machine, the combination of bending devices, a wire twisting device in proximity to said bending devices, means for causing said twisting device to periodically grip the wire, and means for rotating said twisting device alternately in opposite directions, said means including a gear segment connected thereto and provided with oppositely disposed ratchet teeth, pawls engaging said ratchet teeth, a member carrying said pawls, and means for oscillating said member.

75 25. In a wire bending machine, the combination of bending devices, a wire twisting device in proximity to said bending devices, means for causing said twisting device to periodically grip the wire, means for rotating said twisting device alternately in opposite directions, said means including a gear segment connected thereto and provided with oppositely disposed ratchet teeth, pawls engaging said ratchet teeth, a member carrying said pawls, and means for oscillating said member, said means being connected to said bending devices and arranged to be alternately actuated in opposite directions thereby.

80 26. In a wire bending machine, the combination of alternately movable bending devices, a wire twisting device located in proximity to said bending devices, and means connected to one of said bending devices for rotating said twisting device in one direction, and means connected to the other bending device for rotating said twisting device in the opposite direction, to thereby impart a twist or torsional set in opposite directions to successive portions of the wire.

95 27. In a wire bending machine, the combination of oppositely disposed oscillatory bending devices, mechanism for alternately actuating the same, and a clutch member through which the wire is led to said bending devices, said clutch member being arranged to oscillate on an axis normal to the plane of oscillation of said bending devices, means for oscillating said clutch device, and means for causing the same to intermittently grip successive portions of the wire.

100 28. In a wire bending machine, the combination of oppositely arranged oscillatory bending devices and means for alternately actuating the same, a wire twisting device mounted to oscillate on an axis normal to the plane of oscillation of the bending devices, and means for causing the wire twisting device to periodically grip the wire and twist the same.

115 29. In a wire bending machine, the combination of alternately movable anvil mem-

bers, oscillatory benders coöperating therewith, a shaft for moving said anvil members and oscillating said benders, a wire twisting device located in proximity to the 5 bending devices, and means controlled by said shaft for causing said twisting device to twist successive portions of the wire as it is fed to said bending devices.

30. In a wire bending machine, the combination of alternately movable anvil members, oscillatory benders coöperating therewith, a shaft arranged to move said anvil members and oscillate said benders, a wire twisting device located in proximity to said 10 bending devices, means controlled by said shaft for causing the twisting device to periodically grip successive portions of the wire, and means for rotating said twisting device to impart a twist or torsional set to 15 successive portions of the wire as it is fed to 20 said bending devices.

31. In a wire bending machine, the combination of alternately movable anvil members, oscillatory benders coöperating therewith, a shaft arranged to move said anvil members and oscillate said benders, a wire twisting device located in proximity to said bending devices, means controlled by said shaft for causing the twisting device to 25 periodically grip successive portions of the wire, and means for rotating said twisting device alternately in opposite directions during successive grippings of the wire to 30 impart a twist or torsional set in opposite 35 directions to successive portions thereof.

32. In a wire bending machine, the combination of alternately movable anvil members, oscillatory benders coöperating therewith, a shaft for moving said anvil members and oscillating said benders, a wire twisting 40 device located in proximity to said bending devices, means controlled by said shaft for causing said twisting device to periodically grip successive portions of the wire, and means connected to said bending devices for 45 rotating said twisting device to impart a twist or torsional set thereto.

33. In a wire bending machine, the combination of alternately movable anvil members, oscillatory benders coöperating therewith, a shaft for moving said anvil members and oscillating said benders, a wire twisting device located in proximity to said bending devices, means controlled by said shaft for causing said twisting device to periodically 50 grip successive portions of the wire, means connected to one of said benders for rotating said twisting device in one direction, and means connected to the other bending device for rotating said twisting device in 55 the opposite direction, whereby a twist or torsional set in opposite directions is imparted to successive portions of the wire.

In testimony whereof, I have hereunto set my hand.

FRANK L. O. WADSWORTH.
